US0D1008214S

(12) **United States Design Patent** (10) **Patent No.:** **US D1,008,214 S**
(45) **Date of Patent:** **** Dec. 19, 2023**

(54) **EAR PLUGS**

(71) Applicant: **Minuendo AS**, Oslo (NO)

(72) Inventors: **Stian Normann Andersen**, Fredrikstad (NO); **Håkon Auvik**, Oslo (NO); **Vidar Pedersen**, Fredrikstad (NO)

(73) Assignee: **Minuendo AS**, Oslo (NO)

(**) Term: **15 Years**

(21) Appl. No.: **35/515,895**

(22) Filed: **Aug. 4, 2022**

(80) **Hague Agreement Data**

Int. Filing Date: **Aug. 4, 2022**

Int. Reg. No.: **DM/225610**

Int. Reg. Date: **Aug. 4, 2022**

Int. Reg. Pub. Date: **Dec. 30, 2022**

(51) **LOC (14) Cl.** **14-01**

(52) **U.S. Cl.**

USPC **D14/205**

(58) **Field of Classification Search**

USPC D14/205, 223; D24/174; 128/864-866; 381/380-381, 322, 328, 374, 375
CPC H04R 25/00; H04R 25/02; H04R 1/10; H04R 1/1033; H04R 1/1066; H04R 1/1016; H04R 5/033; H04R 5/0335; H04R 1/105; H04R 1/1075; H04R 1/1008; H04R 1/1091

(57) **CLAIM**

The ornamental design for ear plugs, as shown and described.

DESCRIPTION

1. Ear plugs

1.1 : Isometric

1.2 : Front

1.3 : Back

1.4 : Left

1.5 : Right

1.6 : Top

1.7 : Bottom

1 Claim, 7 Drawing Sheets

US D1,008,214 S
